UNITED STATES PATENT OFFICE.

FREDERICH KERSCHBAUM, OF CAMBRIDGE, ENGLAND.

METALLIC-VAPOR LAMP.

1,118,868.

Specification of Letters Patent.

Patented Nov. 24, 1914.

Application filed September 8, 1913. Serial No. 788,770.

To all whom it may concern:

Be it known that I, Dr. FREDERICH KERSCHBAUM, physicist, a citizen of the Empire of Austria-Hungary, residing at Caius 5 College, Cambridge, England, have invented certain new and useful Improvements in Metallic-Vapor Lamps, of which the following is a specification.

The object of the present invention consists in providing an arrangement by means of which the light of a mercury-vapor arc is obtained free from the effect of absorption.

In the drawing a metallic vapor lamp according to the invention is shown by way of example.

Figure 1 is a vertical section, Fig. 2 is a horizontal section, Fig. 3 shows several forms of the vapor arc, Fig. 4 is the spectrum of an ordinary lamp, Fig. 5 is the spectrum of a lamp according to the present invention, Fig. 6 is the spectrum of a resonance-lamp combined with the vapor lamp, Fig. 7 shows the combination of a vapor lamp with a resonance lamp, Fig. 8 is a horizontal section through another form of the vapor lamp, and Fig. 9 is a horizontal section through a further form of the vapor lamp.

Whereas in lightly loaded lamps the illuminating vapor uniformly fills the entire cross-section of the tube between the electrodes (Fig. 3^a of the accompanying drawing), when there is an increased load—and therefore higher temperature—the radiant vapor retreats from the walls of the surrounding tube, and forms an intensively radiant thread of light located in the axis of the tube, surrounded by comparatively weakly illuminating mercury vapor (Fig. 3^b). The light of the bright radiant axial thread must therefore, in order to be able to issue from the lamp, first penetrate the envelop of vapor and undergo absorption.

To obviate this absorption effect, according to the invention the temperature of the envelop is reduced, and hence the concentration of the absorbing vapor is diminished. This can be effected by cooling outwardly; then, however, owing to an abundant condensation of mercury vapor, a coating of mercury forms on the entire inside wall of the lamp and allows almost no light whatever to issue. To prevent the condensation of the mercury vapor according to the invention the arc is electromagnetically de-

flected toward one side of the tube of the lamp. The deflected arc raises the temperature of the tube at the place where it is applied and burns for itself an aperture in the film resulting from condensation. The light of the deflected radiating arc will issue through this aperture without having penetrated an absorbing layer of mercury vapor.

The brass block *b* (Figs. 1 and 2) has a vertical bore; into this are soldered 2 tubes *r* having branches *w* for receiving and discharging the cooling water. Into this vertical cooler is inserted the quartz mercury-vapor lamp *l*, which is fastened above and below by means of the bored rubber stoppers *d*, which fit the tubes *r* and securely close the same. Moreover, in the construction illustrated it is optional which portion of the arc is to be located within the brass block *b*. It is also clear that different lamps of similar construction can also be readily inserted in the apparatus. The quartz lamp *l* itself is a vertically burning lamp, which is of the simplest and compactest construction possible. As leading-in members for the lamp ground-in nickel-steel pins *n* serve. Only the metal of the lower electrode (cathode) is mercury; the anode is a piece of carbon *c* screwed on the end of the upper nickel-steel pin. The brass block *b* has, in addition, two lateral, horizontal, threaded bores *h*. By means of these screw threads the ends of two iron rods *m* are screwed up close to the wall of the lamp; over these rods are pushed coils of wire *e*. In the experimental model each of the two coils has 200 turns of covered copper wire of $\frac{1}{2}$ ohm resistance; the current employed is 2-3 amperes. The electromagnets so formed produce lines of force at right angles to the axis of the lamp. The block *b* has another horizontal bore *f*. This passes through only the rear half of the block and can be closed by a quartz plate *f'* which can be screwed on. When the lamp is burning and the electromagnets are so connected that they deflect the arc to the rear, the light will issue through the bore *f* and the quartz plate *f'*. The lamp is ignited by being rotated into its horizontal position. In the present construction such rotation can be readily effected because parts of the magnets are formed as pivots which rest in corresponding bearings. When the lamp is turned back to the vertical position the arc is then maintained.

A rough comparison of an ordinary mercury vapor lamp burning without water-cooling or magnetic field with the subject-matter of the application shows the difference of their light. Whereas the yellowish blue light of the ordinary lamp can be borne for a short time by the unprotected eye, the whitish blue light of the subject-matter of the application has an unbearable brightness. It is difficult to name conditions under which to base a comparison between the light of an ordinary hot lamp and that of the subject-matter of the application. The loading certainly cannot directly serve as a criterion. It may be most correct to assume that lamps of both types radiate a light comparable in respect to nature and intensity when the weakest lines in the spectrum of these lamps indicate equal intensity, like photographic conditions being assumed. For the weakest lines are independent of absorption. These points of view are borne out by the photographs of the spectrum of an ordinary lamp (Fig. 4), and of the lamp constructed according to the invention (Fig. 5). When these photographs were taken, the spectrographic slit was in both cases 14 cm. from the lamp, the exposure 1 second, while the loading of the ordinary lamp was 5 volts with 2 amperes, and that of the new lamp 3 volts with 6 amperes. (The volts are taken per centimeter length of arc). In this case therefore the loading of the two lamps was so empirically chosen that with like conditions in respect to exposure the weakest lines discernible (the two lines to the far right of Figs. 4 and 5) had very approximately the same intensity. A comparison of the intensity of corresponding lines in Figs. 4 and 5 shows distinctly that in the spectrum of the new lamp the intensity of the bright, and particularly the brightest lines is greater, and that new lines occur. It thus follows that the emitted light is at least qualitatively influenced in the desired manner owing to magnetic deflection. It may here be remarked that Figs. 4 and 5 are illustrative enlargements of spectrograms obtained by a small Hilger quartz-spectrograph. It follows at once that provided the lamp is of sufficient length, the arc can be deflected toward various sides of the tube by means of several magnetic fields. For this purpose it is only necessary that each field of magnetic lines is directed about at right angles to the lamp. Apertures are then formed in the film due to condensation in the tube, and allow the light to issue in any direction desired. In Fig. 8 a lamp is shown in which two pairs of magnets m and m' with the coils e and e' respectively are arranged. Further it is readily seen that the mercury vapor lamp can also burn in a rotating magnetic field. This rotation of the magnetic field can be effected, e.g. by rotat-

ing the electromagnets or—without employing special electromagnets—by means of a rotary field such as is produced by rotary currents. A lamp with a rotary field is shown in Fig. 9. E is an iron ring with the poles E^1 , E^2 , E^3 ; the latter have coils connected to the lines of a three phase circuit. The portion of the arc deflected by the rotary field will then rotate and burn clear an entire ring in the mercury film through which light can issue uniformly in all directions.

The light of the new lamp is devoid of heat rays but extremely rich in ultra-violet rays, and can be advantageously employed for disinfection, for sterilizing water and for similar medical purposes. By combining such a lamp with a γ "resonance lamp" ultra-violet light of the wave-length $\lambda=2536$ is continuously obtained with an intensity and homogeneity such as is out of the question by employing spectrographs or monochromators. Fig. 7 shows such a combination of a vapor lamp with a resonance lamp. The "resonance lamp" is a transparent quartz-glass vessel made out of one piece, a tube with both ends closed; it is supplied with a drop of mercury and exhausted. The energizing light enters in the direction of the arrows P , through two circular screens B along the axis of the tube and into the vapor chamber without striking the side walls of the quartz vessel Q . The light which has penetrated the vapor chamber is intercepted by a black cap k . It is thereby obtained that none of the energizing light can issue owing to dissipation through the cylindrical wall of the resonance vessel. Any light which travels in the direction R of the resonance lamp must therefore be exclusively due to resonance radiation. The resonance lamp can be attached light-tight in front of the aperture of the lamp shown in Figs. 1 and 2 by means of the extension piece A . If the lamp constructed according to the invention is caused to burn and its light to fall in this manner into a vapor chamber of the resonance lamp, and if the slit of the quartz spectrograph is brought into the path of the arrow R and therefore of the expected resonance light, which is ultra-violet, then an exposure of the plate of the spectrograph lasting only three seconds (the slit being 2 cm. from the resonance vessel) yield the spectrum shown in Fig. 6.

The remarks made in reference to absorption in the interior of mercury vapor lamps applies, of course, in principle to all metallic vapor lamps.

I claim:

1. A metallic vapor lamp comprising a quartz tube, a cooling vessel surrounding said quartz tube and a number of magnets arranged around the lamp, the axis of said

magnets being arranged radially to the axis of the lamp, substantially as described and for the purpose specified.

2. A metallic vapor lamp comprising a straight quartz tube having no branches, a cooling vessel surrounding said quartz tube, and two radial magnets on opposite sides of the lamp, substantially as described and for the purpose specified.

10 3. A metallic vapor lamp comprising a quartz tube, a cooling vessel surrounding said quartz tube, and a number of radial magnets arranged at an angle to each other for the purpose of enabling the light of the 15 deflected metallic vapor arc to issue in various directions.

4. A metallic vapor lamp comprising a quartz tube, a carbon anode in said quartz tube, and a number of radial magnets arranged around the lamp, substantially as described and for the purpose specified.

5. A metallic vapor lamp comprising a straight quartz tube having no branches, a carbon anode in said quartz tube, a cooling 25 vessel surrounding said quartz tube, and two radial magnets on opposite sides of the lamp, substantially as described and for the purpose specified.

6. A metallic vapor lamp comprising a quartz tube, a carbon anode in said quartz tube, a cooling vessel surrounding said quartz tube, and a number of radial magnets arranged at an angle to each other for the purpose of enabling the light of the deflected metallic vapor arc to issue in various directions.

7. A metallic vapor lamp comprising a quartz tube, a carbon anode in said quartz tube, a cooling vessel surrounding said 40 quartz tube, and two radial magnets on opposite sides of the lamp, substantially as described and for the purpose specified.

8. A metallic vapor lamp comprising a straight quartz tube having no branches, a cooling vessel surrounding said quartz tube, 45 and a number of radial magnets around the lamp, one pair of said magnets being formed as pivots for rotating the lamp about a horizontal axis substantially as described and for the purpose specified.

50 9. A metallic vapor lamp comprising a straight quartz tube having no branches, a carbon anode in said quartz tube, a cooling vessel surrounding said quartz tube, and a number of radial magnets around the lamp, 55 one pair of said magnets being formed as pivots for rotating the lamp about a horizontal axis substantially as described and for the purpose specified.

10. A method of producing a continuous 60 supply of vibrations having a wave length of 2536 Angstrom units by pressing the vapor arc of a metallic vapor lamp against the wall of the cooled lamp tube and by directing the rays freed in such a manner from the absorption effect into the vapor chamber of a resonance lamp.

65 11. A method of producing a continuous supply of vibrations having a wave length of 2536 Angstrom units by pressing the 70 vapor arc of a metallic vapor lamp against the wall of the cooled lamp tube and by directing the rays freed in such a manner from the absorption effect into the vapor chamber of a resonance lamp, and by absorbing the light having passed the resonance chamber by a suitable screen.

In testimony whereof I have hereunto set my hand in presence of two subscribing witnesses.
